UNITED STATES PATENT OFFICE.

JULIUS BOEKEL, OF PHILADELPHIA, PENNSYLVANIA.

THERMOSTAT.

1,110,477.

Specification of Letters Patent. Patented Sept. 15, 1914.

Application filed December 1, 1912. Serial No. 394,160.

To all whom it may concern:

Be it known that I, JULIUS BOEKEL, a citizen of the United States, residing at Philadelphia, in the county of Philadelphia and State of Pennsylvania, have invented certain new and useful Improvements in Thermostats, of which the following is a specification.

This invention is an improvement on the subject matter of my Letters Patent No. 1,094,362 and relates especially to the circuit-closing float employed therein. Hitherto, so far as applicant is aware, such floats have been made of material, preferably steel, which is subject to superficial oxidation, greatly increasing friction as the float ascends and descends with the mercury or other expansible liquid. The present invention remedies this defect by making the body of said float of non-oxidizable material, suitable to such use, said body having a central bore, wherein is fitted a longitudinal metallic rod having contacts at its ends, the lower contact, as in such application, being adapted to penetrate the more or less oxidized surface of mercury below it and remaining permanently immersed therein, and the upper contact serving to close an electric circuit when the float is carried by the mercury up to a certain point.

In the accompanying drawings: Figure 1 represents a vertical central section of a thermostat embodying my invention, the lower part of the mercury tube or receptacle being broken away, the plunger and the adjusting and set screws being left in elevations, but the float being sectioned; Fig. 2 represents in elevation the float body and its internal rod arranged side by side; and Fig. 3 represents a cross-section through the middle part of the same.

The mercury-tube or reservoir 1 is of usual construction, externally screw-threaded at the top to turn into screw-tapped recess 7 of an insulating block 6, constituting the body of the thermostat. Below said screw-threads, there is a collar 2 on said tube, having a radial stud or screw-post 3, which receives at 4 a wire *a* held by set-screw 5.

Block or body 6 has a vertical guide-passage 8 for the mercury-adjusting plunger 12, of insulating material locked at any point by screw 11 working through the side of said body. The latter has on its top a cylindrical block 19, externally screw-threaded to receive an internally screw-threaded electrically conducting casing 18 and said post and body having an internal, vertical, cylindrical bore 20 extending down through them to an annular shoulder 36 near the bottom of the latter surrounding a central hole 37 which connects the said bore with the upper end of the mercury tube 1.

An adjusting screw 13 works down through the correspondingly tapped top 24 and upper part of said casing and has at its lower end a contact 25 for circuit-closing engagement with a contact 34, carried by the upper end of the float 32 hereinafter described. A longer pin-form or needle-form contact 33 on the lower end of said float is permanently immersed in the mercury and of course penetrates the oxidized surface thereof, also passing through hole 37, in which it is guided. The upper end of said body has an annular groove 38 formed therein for receiving any excess of mercury carried up by said float.

A lateral arm 21, integral with casing 18, receives transversely a wire *b* held by a set-screw 23. The contacts are preferably of platinum.

The parts hereinbefore described are substantially identical in construction, combination and operation with the corresponding ones of my previous application before mentioned, and are set forth merely to make clearer the action of the improved float, hereinafter explained, in coöperation with said parts.

My improved float consists of a cylindrical float body *A* of the material known as bakelite or other material not subject to oxidation. Said float-body is cylindrical in form and fits the bore 20, as closely as is consistent with the necessary freedom of working of said float up and down therein. This body is preferably provided with convex

ends. It has a central bore A' extending longitudinally through it. In this bore is fitted a metal rod B, preferably of steel, extending to or below the lower end of said body and above the upper end thereof and provided at said ends with contacts 33 and 34 hereinbefore mentioned. These contacts are preferably of platinum fitted securely to the rod, the best method being to set them, as shown, into small recesses or sockets in the rod ends.

In practice it is found that some mercury will often work up along the side of the float between it and the wall of the bore 20 15 constituting an easily oxidizable film which will ensure the oxidation of the contiguous surface of said float as well, if the superficial part of said float consist of material subject to such action. This will be avoided by substituting for the steel commonly employed in said floats a material which will not oxidize; but it is of course necessary that such material should be of sufficient weight to descend with certainty 25 in the bore, though fitting it as closely as is practicable; also that the electrical conductivity through the float should be unimpaired. The metal rod B answers both of these requirements, its mass being sufficient 30 for the former, and the circuit when its contact 34 reaches contact 25 being from wire a through mercury tube 1, mercury 22, contact 33, rod B, contacts 34 and 25, screw 13, casing 18 and arm 21 to wire b.

35 The material of the float body A will not be satisfactorily efficient and durable unless it can resist the action of liquids mercural vapor and a certain amount of heat, maintaining its form, firmness of texture and 40 smoothness of surface, considerations which make vulcanized rubber and most vegetable fiber inferior for this use to some specially adapted materials and compositions, of which bakelite is found by practical tests to 45 be among the best. I do not wish, however, to confine myself to any single materials or number of materials, since any substance may be used which will not oxidize and which is capable of unimpeded and continuous use in a bore or passage and in a thermostat controlled by expansible liquid as stated.

Having thus described my invention, what I claim as new and desire to secure by Letters Patent is:

1. In an electric thermostat operated by the expansion of liquid, a circuit closing float consisting of a metallic rod and a body of non-oxidizable material surrounding the 60 same, in combination with electric conductors and contacts making circuit through said rod, expansible liquid under and in contact with said float and a fixed part having

a bore fitting the float in which the latter moves.

2. A circuit-closing float for a thermostat consisting of a body of non-oxidizable material having a longitudinal central bore and a metallic rod fitted into said bore and provided with contacts on its ends extending beyond said body, in combination with a fixed part having a bore fitting said body, in which bore said float moves up and down, a mercury receptacle below said bore which communicates with the latter by means of a hole of less diameter than said bore, and devices adapted to make circuit through said contacts and rod, the lower contact of said float being of sufficient length to extend down through said hole into said receptacle and of sufficiently small diameter to penetrate below the surface of the mercury.

3. A float having a non-oxidizable surface and provided with a longitudinal interior part of heavier material than that of which it is mainly composed and adapted to make electrical contact at both ends, in combination with a fixed part having a bore in which said float moves up and down, a column of conducting liquid arranged immediately under said bore, means for raising and lowering said float, and conductors adapted to make electrical circuit through said rod, the lower contact of said float being adapted to extend down below said bore and to penetrate below the surface.

4. A float for thermostats consisting of a body of non-oxidizable material adapted to retain its form, texture and smoothness and having a central bore, and a metallic rod fitted into said bore and extending through the float at both ends, and having a lower contact sufficiently elongated and of sufficiently reduced diameter to penetrate readily below the surface of mercury, in combination with a mercury column arranged below said bore and means for preventing the descent of the body of the float into the mercury.

5. A float for thermostats consisting of a bakelite body, a steel rod within the same and contacts set into the ends of said rod the lower contact being of considerable length and reduced diameter for the purpose set forth.

6. A float for thermostats consisting of a non-oxidizable body having a bore through it, a metallic rod fitting said bore and a contact of less diameter set into one end of said rod and adapted to penetrate readily 120 the surface of the liquid, the other end of said rod being also provided with a contact for the purpose set forth.

7. In combination with the mercury column of a thermostat and electric circuit 125 conductors for making circuit through the

same, a float rising and falling with said mercury and having a part which penetrates below the surface of the same so as to be continually in electrical contact therewith, 5 a fixed part having a bore fitting said float, and in which said float rises and falls, and a relatively fixed contact above said float, the latter consisting of a non-oxidizable body and a metallic rod extending through the 10 same, said rod being provided on its upper

end with a contact for coaction with said relatively fixed contact substantially as set forth.

In testimony whereof, I have signed my name to this specification in the presence 15 of two subscribing witnesses.

JULIUS BOEKEL.
